UNITED STATES PATENT OFFICE

110,506

DESIGN FOR A STEAM PRESSURE COOKER

Earl O. Vits, Manitowoc, Wis., assignor to Aluminum Goods Manufacturing Co., Manitowoc, Wis., a corporation of Wisconsin

Application March 31, 1938, Serial No. 76,204

Term of patent 7 years

To all whom it may concern:

Be it known that I, Earl O. Vits, a citizen of the United States, of Manitowoc, in the county of Manitowoc and State of Wisconsin, have invented a new, original, and ornamental Design for a Steam Pressure Cooker, of which the following is a specification, reference being had to the accompanying drawing, forming part thereof.

In the drawing:

Figure 1 is a top plan view of the steam pressure cooker, showing my design, and

Figure 2 is an elevational view of the same.

I claim:

The ornamental design for a steam pressure cooker, as shown.

EARL O. VITS.
